UNITED STATES PATENT OFFICE.

JAMES J. WOOD, OF FORT WAYNE, INDIANA, ASSIGNOR TO GENERAL ELECTRIC COMPANY, A CORPORATION OF NEW YORK.

MOTOR-DRIVE.

1,193,105.

Specification of Letters Patent.

Patented Aug. 1, 1916.

Application filed December 17, 1914, Serial No. 877,689. Renewed January 12, 1916. Serial No. 71,804.

To all whom it may concern:

Be it known that I, JAMES J. WOOD, a citizen of the United States, residing at Fort Wayne, in the county of Allen, State of Indiana, have invented certain new and useful Improvements in Motor-Drives, of which the following is a specification.

My invention relates to motor drives, and is particularly applicable to such drives for sewing machines. It has heretofore been proposed to control such a motor drive by means of a system of springs and levers, a circuit closer and a brake, both the circuit closer and brake being controlled by pressure on the treadle through a single actuating connection.

My invention has for its object a novel arrangement of parts whereby pressure on the treadle first closes the circuit of the motor without appreciably releasing the brake, and a continuation of pressure on the treadle progressively decreases the effective pressure of the brake. When the brake is clear, maximum speed is developed and all gradations of speed can be obtained from this maximum to zero by properly regulating the pressure on the treadle.

For a better understanding of my invention, reference may be had to the following description taken in connection with the accompanying drawings, in which—

Figure 1 is a transverse vertical section of a sewing machine embodying my invention with the portions outside the plane of section indicated in dotted lines; Fig. 2 is a fragmentary detail view showing the motor with its controlling devices in normal position; and Fig. 3 is a view similar to Fig. 2, but with the controlling devices in extreme actuated position.

Referring to the drawings in detail, and especially to Fig. 1, 1 is the supporting stand upon the top of which is mounted the usual table 2 and the machine platform 3 in which is countersunk the supporting base 4 having secured thereto the bed plate 5 of the sewing machine. The supporting base 4 is supported within the platform 3 at the rear by means of the socket hinge 6, and at the front by the ledge or shoulder 7, which engages a complementary ledge 8 on the front portion 3' of the platform 3. This front portion 3' is connected with the table 2 by means of the socket hinge 9 so that it may be lifted out of the path of the machine when the ma-

chine and its supporting base 4 are lowered into the storage chamber 10, the base 4 being supported in its lowered position by the stop 10'. The sewing machine proper consists of the usual pillar 11 and horizontal arm (not shown) which supports the drive wheel 13 and contains the usual mechanism for transmitting motion from the drive wheel to the needle bar, and the hollow bed plate 5 containing the usual shuttle and feed mechanism, and means for transmitting motion thereto through the pillar from the drive wheel. A foot power mechanism is mounted in the stand 1, consisting of the treadle 16 pivoted to the stand at 17 and adapted to transmit its motion through a connecting rod 18 to the crank 19 of a main drive wheel 20, power being transmitted from said main drive wheel to the drive wheel 35 of the machine by the driving belt 21. These parts may be of any well known or usual construction.

The motor drive for the machine consists of an electric motor 22 attached to the base plate 5 in any suitable manner, as by means of lugs or brackets 23 and bolts 24 which pass through hollow spacing posts 25. The motor 22 is provided with a brake comprising a brake drum 51 mounted on the spindle or shaft of the motor and a brake shoe 64. A switch 65 is mounted on the motor. The brake and switch are operated by the brake lever 26 and the floating switch lever 27, respectively. The floating switch lever 27 is connected at one end to the switch 65 and at the other end to the brake lever 26 through a retractile spring 28. A retractile spring 29 is also connected to the lever 27 so as to oppose the tension of spring 28. An operating or pull device is connected to the switch lever 27, consisting of an elongated link 30, extending downwardly around and below the brake lever 26, and a chain 31. This pull device is adapted to be connected with the far end of the treadle by means of the hook 32 provided for the purpose. This connection, of course, is made only when the motor drive is to be used. Power is transmitted from the driving pulley 33 of the motor to the pulley 13 of the machine by means of a drive belt 34, the driving belt 21 being loosened or disabled whenever the motor drive is used.

Referring to the controlling mechanism in detail, attention is called to Figs. 2 and

3, in which the motor and controlling mechanism are shown. The motor switch 65 consists of the contact members 36, 37 arranged in V-formation and adapted to be bridged by the conducting roller 38. The roller 38 is carried on the end of a switch arm 39 pivoted at 40 to the casing of the motor. The right hand end of the floating switch lever 27 is provided with an elongated eye 41 or slot 41 which fits over the pivot 40 and slides vertically thereon. A tension spring 42 connects at one end to a pin 43 attached to the free end of the switch arm 39 and at the other end to the switch lever 27 at a point 44 above the line connecting the pin 43 and pivot 40, when the parts are in the normal position shown in Fig. 2. The switch lever 27 is held up in the position shown in Fig. 2 by the relatively strong retractile spring 29, which is connected at one end to the lever at the point 45, and is supported at the other end by a pin 46 fixed in relation to the machine. The pin 46 is carried on the yoke 47, which also carries at its lower end a stop pin 48 for limiting the downward movement of the switch lever 27. The brake lever 26 is pivoted to the motor casing at 49, and carries near its pivoted end a brake shoe 64 pivoted to the lever at 50. This brake shoe is hung off center, as clearly seen from the drawings, which prevents the same from chattering. It is normally held tightly against the brake wheel 51 under tension of the relatively weak spring 28, which connects the free end of the brake lever to the free end of the switch lever 27 at points 52 and 53, respectively. A conducting cord 60 is provided for the purpose of effecting connection of the motor with an electrical supply circuit, which may be either direct or alternating current. The switch lever 27 is operated through the link 30 which is connected thereto at the point 54 and passes downwardly free of the brake lever and on each side thereof, connecting below the brake lever with the chain 31. Suitable stop pins 55 and 56 are carried at the right hand end of the switch lever for bringing the switch lever into positive connection with the switch arm 39 when in either of its extreme positions, so that in case the spring 42 breaks, the switch arm 39 will nevertheless be positively operated by these pins.

The operation of the machine is as follows: Assuming that the motor driving belt 34, the chain 31 and treadle 16 are connected up as shown in Fig. 1, and that the windings of the motor are connected to a suitable source of current in circuit with the switching means, the operator rocks the treadle so as to gradually pull down on the chain 31. As the chain and its link connection 30 move downward, the switch lever 27 first swings around a point to the left of

point 45, the right hand end moving down, guided by the slot 41 and pivot 40, until the uppermost end of the slot engages the pivot. As the right hand end of the switch lever 27 moves downward, it carries the point 44 below the line passing through the pin 43 and pivot 40, so that, just before the upper end of the slot 41 strikes the pivot 40, the direction of pull of the spring 39 is shifted to a point below the center of the pivot 40, which causes the switch arm 39 to snap down into the position shown in Fig. 3, bringing the bridging member 38 into engagement with the contacts 37, 36.

When the switch 65 is actuated to closed position, as above described, the circuit of the motor is completed and the motor armature and field winding are connected in series directly across the supply circuit without the interposition of any resistance, and it therefore immediately exerts its maximum torque. The tension of spring 28 has not however, been appreciably relieved, and consequently the brake 64 is still applied to the motor armature and prevents it from rotating. Further motion of the treadle to pull down on the chain 31 now swings the lever 27 about the pivot 40 and relieves the tension of the spring 28, which relieves the tension on the brake lever 26 and consequently the pressure of the brake 64. The motor armature now begins to rotate, rotating the brake wheel 51 and pulley 33, all of which are connected to rotate together. This motion of the pulley is transmitted to the machine by the drive belt 34 which starts the machine to working. If the tension of spring 28 has been only partially relieved, the pressure of the brake shoe 64 against the brake wheel 51 is only partially reduced, so that the motor and machine run at minimum speed. If the chain 31 is moved downward to its lowest limit, the lever 27 swings about the pivot 40 against the tension of the relatively strong spring 29 until it finally strikes the stop pin 48, the downward movement of the free end of the lever 27 reducing the tension of the spring 28 to a minimum, which in turn reduces the pressure of the brake shoe 64 on the brake wheel 51 to a minimum. The gradual reduction of the tension of the spring 28 to a minimum proportionally reduces the pressure of the brake shoe on the brake wheel, thereby gradually reducing the braking effect on the armature of the motor and permitting a gradual increase of speed until the limit is reached. When the treadle 16 is gradually rocked back so as to permit the switch lever 27 to move back into the normal position indicated in Fig. 2, under tension of the relatively strong retractile spring 29, the switch lever first swings upward around the pivot 40, gradually increasing the tension on spring 28, which in turn gradually increases the pressure of the brake

shoe on the brake wheel of the motor, thereby causing a gradual reduction in the speed of the motor until the motor is finally brought to a standstill, then the spring 29 causes the right hand end of the lever 27 to move upward on the pivot 40 until the lower end of the slot 41 strikes said pivot, which upward movement of the lever again carries the point 44 to its normal position above the dead center line as indicated in Fig. 2. As soon as the point 44 reaches its normal position, the direction of pull of the spring 42 is moved above the center of the pivot 40, which causes the switch arm 39 to snap up into the normal disconnected position, as indicated in Fig. 2, whereby the circuit of the motor is opened. It will thus be seen that by this method of control, the use of complicated flexible transmission is done away with, and that the power output of the motor is regulated directly by the pressure of the foot on the treadle, which method of regulation comes most natural to the operator, and renders the device easy of operation without special instruction in its use.

It is obvious from the drawings that the machine may be pedally operated by disengaging the belt 34 from the drive wheel 13 and throwing the belt 21 into engagement with the drive wheel 35.

It will be obvious to those skilled in the art that various modifications may be made without departing from the spirit of the invention, and I wish it fully understood that all such modifications are contemplated by me as fall within the scope of the appended claims.

What I claim as new, and desire to secure by Letters Patent of the United States is:—

1. In combination, a machine having actuating means, an electric motor adapted to drive said actuating means, and means for controlling said motor comprising a brake drum on the motor spindle, a brake lever, a switch for the motor supply circuit, a floating lever connected at one end to said switch and at the other end through tension means with the brake lever, intermediate tension means connected to said lever so as to oppose the brake lever tension means, and an actuating connection for the switch lever adapted to oppose the last mentioned tension means so that when pressure is exerted upon it the switch will first close and thereafter the strain on the tension device of the brake lever will be progressively decreased.

2. In combination, a machine having actuating means, an electric motor adapted to drive said actuating means, and means for controlling said motor comprising a brake drum on the motor spindle, a brake lever pivoted at one side thereof, a switch for the motor supply circuit, a floating lever connected at one end to said switch and at the other end through tension means with

the brake lever, intermediate tension means connected to said lever so as to oppose the brake lever tension means, and an actuating connection for the switch lever adapted to oppose the last mentioned tension means so that when pressure is exerted upon it the switch will first close and thereafter the strain on the tension device of the brake lever will be progressively decreased.

3. In combination, a machine having actuating means, an electric motor adapted to drive said actuating means, and means for controlling said motor comprising a brake drum on the motor spindle, a brake lever pivoted at one side thereof extending across to the other side and carrying a brake shoe bearing on the drum, a switch for the motor supply circuit, a lever connected at one end to said switch and at the other end through tension means with the brake lever, intermediate tension means connected to said lever so as to oppose the brake lever tension means, and an actuating connection for the switch lever adapted to oppose the last mentioned tension means, so that when pressure is exerted upon it the switch will first close and thereafter the strain on the tension device of the brake lever will be progressively decreased.

4. In combination, a machine having actuating means, an electric motor adapted to drive said actuating means, and means for controlling said motor comprising a drum on the motor spindle, a brake shoe bearing thereon, a transverse lever pivoted at one end and carrying said shoe intermediate of its ends, a switch for the motor circuit, an actuating lever for said switch, a relatively strong tension member extending from said lever to a fixed anchorage, and normally exerting strong tension on the lever to keep the switch open, a relatively weaker tension member connected between the ends of the switch lever and the brake lever and normally maintaining the brake shoe in engagement with the drum under braking pressure, and a pull device connected to the switch lever between the tension devices and the switch, the parts being so arranged and connected that a direct pull upon said pull device will first act against the relatively strong spring to move the switch lever and thereby throw over the switch into closed position, and a continuation of said pull will then move the switch lever upon the switch as a pivot against the tension of the relatively strong spring member, to relax the tension of the relatively weaker tension member and thereby decrease the pressure of the brake shoe upon the braking drum.

5. In combination, a machine having actuating means, an electric motor adapted to drive said actuating means, and means for controlling said motor comprising a brake drum on the motor spindle, a brake shoe

bearing thereon, a lever pivoted at one end to the motor structure and carrying said brake shoe, a make and break switch mounted on the motor field structure opposite the 5 brake mounting, a lever having a slotted connection with said switch so as to allow lost motion, and a pair of tension springs of unequal strength, the weaker spring connecting the outer or free ends of the said 10 lever, and the stronger spring connecting a point near the outer end of the switch lever to a fixed abutment, and a pull device connected to the switch lever at a point between said stronger spring and the switch, 15 whereby a normal distribution of forces will maintain the switch lever in totally retarded position with its slotted end holding the switch open, and its other end maintaining maximum tension on the brake lever spring, 20 but pressure exerted on the pull device will first move the slotted end of the switch lever to close the switch and then will turn said lever upon the switch pivot against the tension of the stronger spring to relax the 25 tension on the brake lever spring.

6. In combination, a machine having actuating means, an electric motor adapted to drive said actuating means, and means for controlling said motor comprising a 30 drum on the motor spindle, a brake shoe bearing on the drum, a pivoted brake lever carrying said shoe, a pivoted make and break switch for the motor circuit, a switch lever having a slot traveling on the same 35 pivot as the switch and having a snap spring connection with the switch arm adapted to be moved past center in one direction or the other as the lever moves from side to side to the limits of its slot, a tension spring connecting the free ends of the 40 brake lever and the switch lever, and a stronger tension spring opposing the first mentioned spring and connecting an intermediate point on the switch lever to a fixed 45 anchorage, tension on said stronger spring normally maintaining the switch lever at its pivot end retracted to the limit of its slot and the switch open, and at the other end retracted against the weaker tension 50 spring to place the strain upon the brake lever, and a pull device secured to the switch lever at a point between the connection of the stronger spring and the pivot slot, the pull device when operated acting against the 55 stronger spring to first pull over the switch end of the lever to the limit per-

mitted by its slot and thereby close the switch, and thereafter to overcome the tension of the stronger spring and move the free end of the switch lever around the 60 switch pivot so as to relax the tension on the brake spring and thereby the pressure exerted by the brake on the drum.

7. In combination, a machine having actuating means, an electric motor adapted to 65 drive said actuating means, and means for controlling said motor comprising a drum on the motor spindle, a brake shoe bearing on the drum, a pivoted brake lever carrying said shoe, a pivoted make and break 70 switch for the motor circuit, a switch lever having a slot receiving and traveling on the pivot of the switch and having a snap connection with the switch arm and a pair of opposite stop pins for holding the switch 75 open or closed, according to the position of the lever, said snap spring adapted to be moved past center in one direction or the other as the lever moves from side to side to the limits of its slot, a tension spring connecting the free ends of the brake lever and the switch lever, and a stronger tension spring opposing the first mentioned spring and connecting an intermediate point on the 80 switch lever to a fixed anchorage, tension on 85 the said stronger spring normally maintaining the switch lever at its pivot end retracted to the limit of its slot and the switch open, and at its other end retracted to pull on the weaker tension spring and thereby 90 place a strain upon the brake lever, and a pull device secured to the switch lever at a point between the connection of the stronger 95 spring and the pivot slot, the pull device when operated acting against the stronger 100 spring to first pull over the switch end of the lever to the limit permitted by its slot and thereby close the switch, and thereafter acting against said pivot as a fulcrum to overcome the tension of the stronger 105 spring and move the free end of the switch lever around the switch pivot so as to relax tension on the brake spring and thereby the pressure exerted by the brake on the drum.

In witness whereof, I have hereunto set my hand this 9th day of December, 1914.

JAMES J. WOOD.

Witnesses:

A. L. HADLEY,
C. A. BORCHERT.

It is hereby certified that in Letters Patent No. 1,193,105, granted August 1, 1916, upon the application of James J. Wood, of Fort Wayne, Indiana, for an improvement in "Motor-Drives," an error appears in the printed specification requiring correction as follows: Page 4, line 74, claim 7, after the word "snap" insert the word *spring*; and that the said Letters Patent should be read with this correction therein that the same may conform to the record of the case in the Patent Office.

Signed and sealed this 5th day of September, A. D., 1916.

[SEAL.]

F. W. H. CLAY,

Acting Commissioner of Patents.

Cl. 172—179.
